US00D730535S

(12) **United States Design Patent** (10) **Patent No.:** **US D730,535 S**
Gutmann et al. (45) **Date of Patent:** **** May 26, 2015**

(54) **PCR INSTRUMENT**

(71) Applicant: **Roche Molecular Systems, Inc.**,
Pleasanton, CA (US)

(72) Inventors: **Peter Gutmann**, Thalwil (CH); **Jan Muegel**, Berlin (DE); **Therese Naeff**, Nussbaumen (CH); **Britta Pukall**, Waedenswil (CH); **Johann Florian Wassermann**, Horgen (CH)

(73) Assignee: **Roche Molecular Systems, Inc.**,
Pleasanton, CA (US)

(**) Term: **14 Years**

(21) Appl. No.: **29/468,450**

(22) Filed: **Sep. 30, 2013**

(30) **Foreign Application Priority Data**

Apr. 3, 2013 (WO) DM/080 913

(51) **LOC (10) Cl.** **24-01**

(52) **U.S. Cl.**

USPC **D24/216**

(57) **CLAIM**

The ornamental design for a PCR instrument, as shown and described.

DESCRIPTION

FIG. 1 shows a front elevational view of a PCR instrument;
FIG. 2 shows a right perspective view thereof;
FIG. 3 shows a left perspective view thereof;
FIG. 4 shows a right side elevational view thereof;
FIG. 5 shows a left side elevational view thereof;
FIG. 6 shows a top plan view thereof;
FIG. 7 shows a bottom plan view thereof; and,
FIG. 8 shows a rear elevational view thereof.
The broken lines depict unclaimed environmental subject matter.
